Des. 198,938
Patented Aug. 18, 1964

198,938

OPTICAL COMPARATOR FOR PRINTED MATTER AND THE LIKE

George R. Kent, Minneapolis, Minn., assignor to Colight,
Inc., Minneapolis, Minn., a corporation of Minnesota

Filed Feb. 27, 1963, Ser. No. 73,744

Term of patent 14 years

(Cl. D57—1)

FIG. 1

FIG. 2

FIG. 3

FIG. 4

FIG. 1 is a front perspective view of an optical comparator showing my new design;

FIG. 2 is a rear perspective view thereof;

FIG. 3 is a front elevational view of the same; and

FIG. 4 is a side elevational view thereof.

The electric cord member disclosed in FIGS. 2 and 4 is fragmentarily shown for convenience of illustration.

I claim:

The ornamental design for an optical comparator for printed matter and the like, substantially as shown and described.
